UNITED STATES PATENT OFFICE.

BURTON S. AIRMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PUMP.

1,256,092.

Specification of Letters Patent. Patented Feb. 12, 1918.

Application filed March 27, 1917. Serial No. 157,807.

To all whom it may concern:

Be it known that I, BURTON S. AIRMAN, a citizen of the United States, residing at Milwaukee, in the county of Milwaukee and State of Wisconsin, have invented a certain new and useful Improvement in Pumps, of which the following is a full, clear, concise, and exact description, reference being had to the accompanying drawings, forming a part of this specification.

My invention relates generally to pumps and particularly to pumps employed in a system operating on faucet control.

Systems of this type are particularly useful for isolated plants as where residences or industrial establishments are to be furnished with water from a well. The invention, however, is not to be limited to such use.

20 The pump proper is sunk in the well under a suitable head of water; the discharge main is connected to the distributing pipe; the air inlet is connected to a source of compressed air and the exhaust is connected to the atmosphere.

The pump operates as long as it is supplied with compressed air and has a free outlet. If the outlet is completely shut off as where all the faucets are closed the pump becomes stalled by back pressure and ceases to operate. As soon as an outlet is provided as by opening a faucet the pump again operates, there being then a drop of pressure permitting operation. As the running of the pump is dependent upon the provision of an outlet as by opening the faucets this type of system is designated a faucet control system.

Such operation provides fresh water on demand because it dispenses with storage of the water in a tank which is characteristic of level control pumping systems. The well itself is the only supply tank.

Pumps operating on faucet control have heretofore been used but they have been of intricate construction, costly in manufacture and operation and subject to certain defects in operation.

My invention aims to provide a pump of simple structure, inexpensive to manufac-

ture and positive in operation. The invention also provides improved means for obtaining a quick and positive throw of the control valve.

The particular type of pump that I have chosen to illustrate my invention is of the single cylinder type and inasmuch as the employment of a single cylinder pump in a faucet control system is my invention as can be seen from the copending application, Serial No. 50,941, filed by me September 16, 1915, I shall illustrate diagrammatically the system in which the pump is designed to operate.

In the accompanying drawings which form a part of the present specification, Figure 1 is a diagrammatic view illustrating the system as a whole;

Fig. 2 is a plan view of the pump;

Fig. 3 is a vertical axial section taken on the plane of the line 3, 3, of Fig. 2 and looking in the direction indicated by the arrows;

Fig. 4 is a vertical axial sectional view taken on the plane of the line 4, 4, of Fig. 2 and looking in the direction of the arrows; and

Fig. 5 is a sectional view taken on the plane of the line 5, 5, of Fig. 3 and looking in the direction of the arrows; and Fig. 6 is an enlarged fragmentary sectional view of the valve shown in Fig. 3.

As shown diagrammatically in Fig. 1, the pump 10 is disposed in the well, the curbing of which is shown at 8 below the level 9 of the water so that the pump automatically fills at the proper time as will be described later. The pump structure has leading therefrom three pipes, an air pressure pipe 11, an exhaust pipe 12 and a water discharge pipe 13. The air pressure pipe 11 is connected with a compressed air tank 14 in which air is stored under pressure as by means of a suitable motor driven compressor 15 having a driving electric motor 16. It will be apparent to those skilled in the art that the compressor may be operated by any other motor such as a gas engine, steam engine or the like, and if desired means may be provided for automatically starting and

stopping the motor when the pressure in the tank drops to a prescribed minimum and rises to a prescribed maximum respectively. The pipe 11 is connected to the tank 14 through the cut off valve 11^a, the air strainer 11^b, the reducing valve 11^c. A pressure gage 11^d and drain cock 11^e are provided in connection with the pipe 11.

The water discharge pipe 13 leads to various branch pipes 17 and 18 each of which in turn is provided with a faucet 19. The water supply system is connected as by means of the pipe 20 to a tank or chamber 21 in which is trapped a quantity of air forming an air cushion the purpose of which will be pointed out later.

It can now be understood that this system represents an isolated plant for installation in a residence or the like. The water discharge pipe leads from the well conveniently near by to the distributing pipe in the building and the compressor, motor, compressed air tank and chamber may be suitably housed in any convenient manner.

As before pointed out the pressure is constantly maintained upon the system. It is therefore necessary to maintain a certain pressure between predetermined minimum and maximum limits in the compressed air tank 14, this being done by the proper starting and stopping of the compressor 15 either manually or automatically. It has been my experience that a proper compressed air tank being provided it is necessary in employing a distributing system for an ordinary residence, for instance, to operate the compressor only intermittently every two or three days for a short time in order to keep the pressure in the compressed air tank within desired limits.

It will be apparent from the following description that with the pressure properly maintained upon the system, the pump remains entirely at rest so long as all the outlets faucets of the system are closed, but as soon as one of the faucets is opened the pumping mechanism will operate to maintain continuous the flow through the outlet in an endeavor to maintain the pressure in the system constant. When the faucet is again closed the flow ceases and the apparatus comes to rest because of equalization of the pressure. Thus it is apparent that the feed has been direct from the well with the proper pressure to distribute it to whatever point desired.

The pump 10 is shown in detail in Figs. 2 to 5. The pump comprises a cylindrical barrel 23, preferably in the form of a piece of seamless brass tubing. The upper end of the barrel 23 is closed off by a head casting 24 and the lower end of the barrel is closed off by the foot casting 22. The head casting 24 and the foot casting 22 are held

together upon the ends of the barrel 23 by means of the pipes 25 and 26. These pipes are screwed into suitable openings provided at the lower ends of the legs 27 and 28 which are a part of the head casting 24. At their lower ends the pipes 25 and 26 extend into suitable sockets 29 and 30 where they are held by the screw plugs 31 and 32 which I have shown in the shape of flat head machine screws which pass through suitable apertures in the foot piece 22. Suitable packing as shown at 33 and 34 serves to make a tight joint between the ends of the barrel and the top and bottom pieces respectively.

The foot casting 22 is provided with a central hollow chamber 35 which communicates with the interior of the barrel only through the medium of the check valves 36 and 37. These check valves are normally held upon their seats by suitable springs 38 and 39 being guided by their stems 40 and 41 in the bracket member 42. The chamber 35 communicates with the exterior through the conical screen 43 which is held in place by the central stud 44 and the cap 45.

The head casting 24 is provided with a compressed air inlet 46 which communicates with a central chamber 47 and a passageway 48 in the body of said casting. The head casting is also provided with a water outlet connection 49 and an exhaust outlet 50. The water outlet 49 communicates with a chamber 51 which extends to the check valves 52 and 53 which separate the chamber 51 from the passageways 54 and 55 that are formed in the downwardly extending legs 27 and 28. The legs 27 and 28, as previously described, are connected to the pipes 25 and 26. At their lower ends the pipes 25 and 26 are provided with a number of holes as shown at 56 and 57, permitting communication with the interior of the barrel 23. The check valves 52 and 53 are provided with suitable seats formed in the head casting 24 and are guided upon these seats by means of the plugs 58 and 59 which embrace the stems of the valves 52 and 53 respectively. Suitable springs 60 and 61 normally hold the check valves 52 and 53 in place.

The exhaust outlet 50 communicates with a diagonal passageway and chamber 62.

The head casting 24 has secured upon the bottom thereof a valve casting 63 provided with valve-passages later to be described and provided also with a chamber or cylinder 64 closed off by a flexible piston or diaphragm 65 which is clamped upon the open end of the head casting 24 by means of the valve casting 63. The flexible diaphragm 65 forms the valve operating piston for operating the compressed air inlet and exhaust valves 66 and 67 respectively, as will

be described later. The valve body 63 has a passageway 68 which communicates with the passageway 48 and the compressed air inlet 46. The exhaust chamber 62 is connected to a passageway 69 in the valve body 63. This passage ends in a suitable valve port 70 opening into a passageway 71 leading to the valve operating cylinder 64. The valve body 63 is suitably recessed to receive a valve supporting plug 72 which supports a double faced valve 73 in line with the port 70 and which has a valve passage communicating with the passage 68 and forming a valve port 74 adapted to be controlled by the back of the valve member 73. The valve member 73 has a stem 75 projecting out of the plug 72 and provided with a collar 76 by which the valve is operated. The valve 73 is adapted to cover either the port 70 or the port 74 and in order to secure this result and to prevent the valve taking an intermediate position a snap operating mechanism is provided. A shaft 77 is mounted in the ears or bracket 78 upon which is pivoted the bell crank lever 79 and the operating arm 80. The bell crank lever 79 has the fingers 81 which embrace the collar 76 and are adapted to move the valve 73 in and out. The opposite end of the bell crank lever is provided with the projecting pins 82 and 83 which are connected at their ends to the springs 84 and 85. The operating arm 80 is connected at its outer end to a shaft 86 to which the other ends of the springs 84 and 85 are connected. The operating arm 80 is operatively connected to the water weight 87 by means of the link 88. A water weight 87 comprises a hollow cylindrical body consisting of a shell of metal 89 preferably a tube of brass or bronze, or the like, having its lower end closed by a head 90, this head being provided with a guiding pin 91 which is guided in a suitable bracket 92 clamped to the pipes 25 and 26. The float or water weight 87 is provided with a spring 93 for counterbalancing a part of the weight of the same. The compressed air controlling valve 66 normally rests upon a seat 94 which forms a port permitting communication of the chamber 47 with the space 95, which space 95 in turn communicates with the barrel 23 through the screen ring 96. The screen ring 96 has a number of apertures covered by fine wire screens to prevent any foreign matter being introduced with the compressed air into the pump. The valve 66 comprises a guiding stem 97 which fits closely into the sleeve 94. This valve is normally held on the seat by the spring 98 housed in the plug 99 which plug is secured in a suitable aperture in the top surface of the head member 24.

The exhaust valve 67 is provided with a

yielding seat member 100 which is adapted 65 to engage the seat members 101 and 102 which define an annular passage or port 70 communicating with the exhaust passage 62. The valve 67 is loosely mounted on the cylindrical stem 103, this stem being provided with an enlargement 104 fitting within the guiding sleeve 105 and lying axially in line with the stem 97 of the valve 66 which admits air under pressure. The valve 67 is held against the shoulder of the enlarged 75 portion 104 by means of a spring 106, the stem 103 being clamped to a pair of disks 107 and 108 between which is secured the operating diaphragm 65.

Assume that the pump is connected in the 80 system as shown in Fig. 1 and that compressed air is supplied. Assume also that one of the outlets such as the faucet 19 is opened and that the parts of the pump are in the position shown in Figs. 3 and 4. 85

At this time the compressed air is shut off as the valve 66 is seated upon its port 94 closing off the compressed air from the interior of the chamber 23. The double faced valve 73 is held in the position shown thus 90 covering the port 74 which communicates by way of the passage 68 with the compressed air supply. The exhaust port 70 is uncovered and the exhaust valve is also opened thereby placing the interior of the 95 barrel 23 in communication with the atmosphere. The water weight 87 is in its lower position, having been moved into that position by a reduction of the level of the water in the pump, the pump being now in the 100 position of having completed a stroke and beginning to fill with water. As the level of the water rises in the barrel 23 the water weight or float 87 tends to rise. As this body is relatively long and of small cross 105 section a considerable difference in level is required to make any great difference in the upward pressure exerted by it through the link 88. The springs 84 and 85 being at present below the center line of the shaft 77 110 tend to hold the float down until the upward thrust becomes such as to overcome the springs and when this occurs the arm 80 is quickly thrown over the center by the snap action of the springs 84 and 85, throwing the water weight to the extreme upper position. When the shaft 86 moves above the center of the shaft 77, the springs 84 and 85 exert an upward pull upon the bell crank lever 79 and the bell crank is moved upward with a snap action suddenly shifting the double face valve 73 from the port 74 to the port 70, thus the cylinder for the diaphragm 65 is shut off from exhaust and is connected to the source of compressed air 120 through the passageways 68 and 48 from the chamber 47. As the pressure rises in the cylinder 64 the flexible diaphragm 65 is

forced upward and the stem 103 rises. The first result from this movement is that the exhaust valve 67 closes off the exhaust port by bringing the yielding face of the valve into contact with the seat members 101 and 102. Having brought the exhaust valve to the closed position, the stem 103 continues to rise bringing the enlarged portion 104 against the guiding stem 97 of the admission valve 66 forcing this valve off of its seat and permitting compressed air to pass from the chamber 47 into the space 95 above the diaphragm 65 and into the space above the water in the barrel 23. The water is immediately driven out through the check valves 52 and 53 into the supply pipe 13 lowering the level of the water in the barrel 23. The pressure upon both sides of the diaphragm 65 is substantially equalized but the exhaust valve does not open being held against its seat by the pressure of the air in the space 95. The valve 73 is also held against the port 70 by the pressure of the air within the chambers 64 and 71. As the water is driven out the water weight or float 87 tends to drop due to the withdrawal of the supporting effect of the water and when the downward pull on the link 88 has become great enough to overcome the tension of the springs 84 and 85 the arm 80 will snap to its lowermost position and at the same time the bell crank 79 which controls the valve 73 will snap into the position shown in Fig. 3 thereby connecting the cylinder 64 with the exhaust passage 69 and simultaneously closing off the port 74 for compressed air. As a consequence the pressure in the cylinder 64 drops and the pressure of the air above the diaphragm 65 forces this diaphragm downward first closing the valve 66 and then opening the exhaust valve 67.

So long as water is moving out of the pump the pressure on the under side of the diaphragm 65 does not equal that upon the lower side and the admission valve 66 is held open. In case the pressures become equalized, as when the faucets are all closed, the valve 66 may close. As soon as the faucets are opened the pressure in the pump drops due to expansion of the air, and expulsion of the water and the pressure on the lower side of the diaphragm 65 then preponderates and pushes the diaphragm up. It will be noted that the stem 103 in its downward motion due to the excess of pressure on its upper side first disengages the stem 97 of the admission valve 66 permitting it to close under the influence of its spring 98 and thereafter the shoulder of the enlarged stem 104 strikes the exhaust valve 67 withdrawing it from its seat and permitting the pressure within the valve to escape to the exhaust port. It is therefore evident

that it is impossible for both the admission valve and the exhaust valve to be opened at the same time, consequently no direct movement of the air through the pump, without performing the work which it is designed to perform, is possible. It is to be noted that the springs 84 and 85 serve to produce a snap action of the movement of the water weight or float 87 and this in turn produces a snap action for the operation of the valve 73.

If the outlets, such as the faucets 19, are completely closed off the pump will cease to operate being stalled by back pressure.

The speed with which the barrel fills depends upon the size of the inlet but in practice this is so rapid that there is scarcely any intermission in the pressure delivered to the pipe 13. The air cushion in the chamber 21 fills in the gap so that at the faucets 19 the flow of water is constant and no cessation of the pressure is noticeable. The air cushion is maintained by a constant infiltration of bubbles of air and if this should become excessive it would be carried over into the faucet 19 and there released as soon as the faucet is opened, this action being imperceptible.

It is apparent that suction instead of full atmospheric pressure might be applied to the pipe 12 without departing from the spirit and scope of the invention.

I do not intend to be limited to the precise details of construction shown and described, as the invention may appear in a variety of forms.

What I claim is:

1. In a pump of the class described a closed water cylinder, a valve and means for admitting compressed air at the upper end of said cylinder, a discharge pipe connected to the bottom of the cylinder, an exhaust valve, a valve operating cylinder for operating said admission valve and said exhaust valve in predetermined order, a valve controlling said operating cylinder, means for imparting a snap action to said last mentioned valve for opening and for closing the same and means controlled by the level of water in the cylinder governing said snap imparting means.

2. In combination, a closed pump cylinder, an inlet valve for said cylinder, an outlet valve for said cylinder, a level controlled device in said cylinder, a balancing spring for said level controlled device, a fluid pressure admission valve, an exhaust valve, a cylinder for operating said valve, and valve means controlling said cylinder, and a spring connecting said water weight and said last named valve.

3. In combination, a closed pump cylinder, a water inlet valve for said cylinder, a water outlet valve for the cylinder, a level con-

trolled device in said cylinder, a balancing spring for said level controlled device, a fluid pressure admission valve, an exhaust valve, a motor for operating said valve, controlling means for said motor, and means controlled by said water weight for imparting a snap action to said controlling means.

4. In combination, a pump cylinder, said cylinder comprising a vertical passageway, a vertical discharge pipe, said pipe and said cylinder being connected at their lower ends, a check valve controlling the outlet from said discharge pipe, a check valve governing the inlet to the bottom of the cylinder, a valve for admitting compressed air at the top of the cylinder, a level controlled device in said cylinder, a compressed air admission pipe for the cylinder, an exhaust valve, an air motor for operating said valve, a valve controlling said motor and a spring controlling said valve and said water weight.

5. In combination, a pump cylinder, said cylinder comprising a vertical passageway, a vertical discharge pipe, said pipe and said cylinder being connected at their lower ends, a check valve controlling the outlet from said discharge pipe, a check valve governing the inlet to the bottom of the cylinder, a valve for admitting compressed air at the top of the cylinder, a level controlled device in said cylinder, a compressed air admission pipe for the cylinder, an exhaust valve, an air motor for operating said valve, a valve controlling said motor, and a spring causing snap action of the valve and controlling the operation of the level controlled device.

6. In a pump, a cylinder, an admission valve, an exhaust valve axially in line with said admission valve, said valves facing toward each other, ports for said valves, a stem for operating both of said valves, said stem having a shoulder, one of said valves being slidable on said stem, a spring for holding said valve against said shoulder, a diaphragm for operating said stem, said diaphragm having a free space upon one side thereof communicating with the space between the valves, a cylinder on the other side of the diaphragm, an admission port and an exhaust port for said cylinder, valve means governing said ports, said ports communicating with the compressed air inlet and with the exhaust outlet respectively, and means controlled by the level of water in the pump for operating last said valve means.

7. In combination, a pump barrel forming an operating cylinder, a level controlled member in said cylinder, a head closing the top of the barrel, a compressed air inlet in said head, an exhaust outlet in said head, an exhaust valve in said head, a diaphragm below said head, a valve body secured to said head, and clamping said diaphragm in place,

said body having a cylinder below the diaphragm, valve means governing said cylinder, said body having passages leading from the air inlet and exhaust outlet to said valve means, a shaft, a pair of arms separately pivoted on said shaft, one of said arms being connected to said valve means, the other arm being connected to said level controlled member, and a spring connecting said arms to impart a snap action to said valve means.

8. In a pump, an operating cylinder, a compressed air inlet, an admission valve between the inlet and the cylinder, an exhaust outlet, an exhaust valve between the outlet and the cylinder, a common stem for operating said valves, said stem being adapted to close the exhaust valve before the admission valve is open, a piston diaphragm communicating on one side with the pressure in the pump cylinder and having a cylinder on the other side thereof, said piston being connected to said stem, a pair of valve ports for said cylinder, said ports communicating with the air inlet and the exhaust outlet respectively, valve means for covering said ports one at a time, snap action means for operating said valves and level controlling means governing said snap action means.

9. In combination, a pump barrel forming a cylinder, a head closing the top of the barrel, an outlet water valve in the head, a foot member closing the bottom of the barrel, a water inlet valve in said foot member, a pipe mechanically securing the head and foot members together, an air inlet and an exhaust outlet in said head, valve means governing the communication of said inlet and said outlet connections with the operating cylinder, an operating motor for said valve means, control means for the motor, a water weight for operating said control means, said water weight being disposed in said barrel, guiding means for the lower end of the water weight, said guiding means being supported on said pipe, a counter-balancing spring for said water weight, a pivoted arm connected to the upper end of the water weight, and a spring for opposing movement of the outer end of the arm past the center of the pivoted end.

10. In combination, a pump cylinder, a head for said cylinder, a compressed air inlet and an exhaust outlet in said head, valves for connecting said inlet and said outlet to the pump cylinder, an air motor for operating said valves, a control valve for said motor, ports for said valves communicating with the air inlet and the exhaust outlet, a water weight of relatively small cross-section extending throughout the greater length of the pump cylinder, a counterbalancing spring for said water weight, a horizontal shaft, an arm loosely mounted on said shaft, the outer end of the

- 6
- arm being connected to said water weight, and a spring connected to said arm, said spring tending to prevent movement of the end of the arm up or down past the central horizontal plane of said shaft.
- 5 11. In combination, a pump cylinder, a head for said cylinder, a compressed air inlet and an exhaust outlet in said head, valves for connecting said inlet and said outlet to the pump cylinder, an air motor for operating said valves, a control valve for said motor, ports for said valves communicating with the air inlet and the exhaust outlet, a water weight of relatively small cross section extending throughout the greater length of the pump cylinder, a counterbalancing spring for said water weight, a horizontal shaft, an arm loosely mounted on said shaft, the outer end of the arm being connected to said water weight, and a spring connected to said arm, said spring tending to prevent movement of the end of the arm up or down past the central horizontal plane of said shaft, and a valve operating arm pivoted on said shaft and having its outer end also connected to last said spring.
- 10 12. In a pump, the combination of a controlling valve, a float device of small cross section and relatively great length, a substantially horizontal shaft, an arm pivoted to said shaft and having its outer end connected to said float device, a spring secured to said arm and extending past the center of said shaft, said spring tending to prevent 15 rotative movement of said arm about said shaft.
- 15 13. In a pump, the combination of a controlling valve, a float device, a substantially horizontal shaft, an arm extending on one side of the shaft, the outer end of the arm being connected to said float device, a valve operating arm extending on the other side of said shaft and a spring connecting the outer ends of both of said arms, said spring being movable above and below the center of said shaft.
- 20 14. In a pump, the combination of a controlling valve, a float device of relatively great length and relatively small cross section, a counterbalancing spring extending from the lower end of said float device along the interior thereof to a supporting point above the same, a shaft, an arm pivoted on said shaft and having its outer end connected to said float device, an operating arm for the valve, and spring means connecting said arms, said spring means tending to retard the movement of the water weight up or down as the case may be and serving to implement a snap action to the valve operating arm.
- 25 15. In combination, a main pump barrel, main valves for the same, a motor for shifting said valves, a controlling valve for said motor, a float device, said valve being controlled by said float device, a rocker shaft, a rocker arm between the shaft and the float, a spring attached to the rocker arm and also beyond the center of the rocker shaft for holding the float down against the buoyant effect of the liquid when the pump is filling and to hold the float up against gravity when the pump is being emptied.
- 30 16. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 35 17. In a pump, a barrel, a head member having an admission passageway, an exhaust passageway, an intermediate passageway between them, a transverse opening connecting said passageways, an admission port between the admission passageway and the intermediate passageway, a valve having a hollow stem guided in said port, said stem having transverse openings through the walls thereof, an exhaust valve for controlling the exhaust passageway, a stem having a shoulder, said exhaust valve fitting loosely on said stem and being adapted to engage said shoulder, means connected to said stem for operating said valves and a spring between the exhaust valve and said means.
- 40 18. In combination, a pump barrel having a head member, said member having an admission passageway, an exhaust passageway and an intermediate passageway between them, ports connecting the intermediate passageway with the exhaust passageway and the admission passageway, an admission valve having a hollow stem guided in said admission port, a stem axially in line with said admission valve stem and adapted to engage the same, an exhaust valve slidably mounted on said stem, said stem having a shoulder for engaging said valve, and a spring for holding said valve against said shoulder.
- 45 19. In combination, a pump barrel having a head member, said member having an admission passageway, an exhaust passageway and an intermediate passageway between them, ports connecting the intermediate passageway with the exhaust passageway and the admission passageway, an admission valve having a hollow stem guided in said admission port, a stem axially in line with said admission valve stem and adapted to engage the same, an exhaust valve slidably mounted on said stem, said stem having a shoulder for engaging said valve, and a spring for holding said valve against said shoulder.
- 50 20. In combination, a main pump barrel, main valves for the same, a motor for shifting said valves, a controlling valve for said motor, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 55 21. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 60 22. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 65 23. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 70 24. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 75 25. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 80 26. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 85 27. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 90 28. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 95 29. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 100 30. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 105 31. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 110 32. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 115 33. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 120 34. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.
- 125 35. In a pump, the combination of a controlling valve, a float device, said valve being controlled by said float device, a rocker shaft, a rocker arm between the shaft and the float, and a spring attached to the rocker arm and also attached beyond the center of the rocker shaft for holding the float down against the buoyant effect of the liquid when the pump is filling and to hold the float up against gravity when the pump is being emptied.

shoulder, and pressure operated means for moving said stem, said spring being mounted between the valve and the pressure operated means.

5 20. In combination, a pump barrel, a head member for the same, an admission passageway, an exhaust passageway, an intermediate passageway between them, a transverse opening connecting all of said passageways, 10 an admission valve having a hollow stem guided in said transverse opening, an annu-

lar sleeve mounted in said transverse opening, a separate stem for the exhaust valve mounted in said annular sleeve, said exhaust valve stem being adapted to engage the admission valve stem, an exhaust valve yieldingly mounted on said stem and a diaphragm connected to said exhaust valve stem.

In witness whereof, I hereunto subscribe my name this 16th day of March, A. D. 1917. 15 20
BURTON S. AIKMAN.
